UNITED STATES PATENT OFFICE

MONTE W. WALKUP, OF CHICAGO, ILLINOIS

BENDING DEVICE

Application filed August 26, 1927. Serial No. 215,576.

- The invention relates to bending machines and more particularly to a device for imparting a curvature to lathing such as corner beads, used as a support for plastering.
- 5 It is an object of the invention to provide a device of the character described which is of simple construction and yet efficiently meets the requirements of curving lathing and particularly corner beads.
- 10 A further object aims at providing a device capable of imparting a predetermined curvature to lathing.
- A still further object constitutes the provision of a device capable of imparting different curvatures to lathing in accordance with special requirements.
- 15 It is also an object to provide certain details of construction and arrangement tending to enhance the efficiency and reliability of a device of this character.
- With these and other objects in view which will become more apparent from a description of the invention, the latter comprises the means described in the following specification, particularly pointed out in the claims forming a part thereof and illustrated in the accompanying drawings, in which:
- Fig. 1 is a top plan view of the device constructed in accordance with my invention;
- 20 Fig. 2 is an elevational view of the device;
- Fig. 3 is a section on the line 3—3 of Fig. 2;
- Fig. 4 is a section on the line 4—4 of Fig. 2;
- Fig. 5 is a section on the line 5—5 of Fig. 3.
- The device shown in the drawings is intended primarily for the bending of lathing and particularly corner beads, but its use may be extended wherever articles are to be provided with a curvature.
- Referring to the various views in the drawings, 10 designates a base plate which is supported by a plurality of legs 11. To the base plate 10, near one end thereof, a U-shaped member 12 is secured so that the cross member 13 thereof abuts the plate and is fastened thereto by a plurality of threaded members 14. The upstanding legs 15 and 16 of the member 12 are of unequal height. To the leg 15 a roller 17 is rotatably secured by a through bolt 18. A plurality of elongated, horizontal rollers 19 and 20 are secured in superposed relation to the leg 16 of the U-member 12. The rollers are mounted on through bolts 21 and 22, respectively, which are held to the leg 16 by nuts 23 and 24 abutting both sides of the leg 16. The latter is provided with an elongated slot 25 through which the bolts 21 and 22 project, so that adjustment of the rollers 19 and 20 is possible.
- 55 A U-member 26 is secured to the base plate 10 near the opposite end thereof and its construction and associated parts are in all respects identical with the first described U-member 12. Further description thereof is deemed, therefore, superfluous.
- 60 Intermediate to the U-members 12 and 26 and centrally of the base plate 10 an angular member 27 is provided. The horizontal leg 28 of said member is parallel to the base plate 10 and its free end is slotted to receive therein a circular lug 29 of a bearing plate 30 which is also parallel to the base plate and adapted to bear thereon.
- 65 A bolt 31 extends through aligned apertures in the lug 29 and the prongs 32 produced by the slotting of the horizontal leg 28 whereby the angular member 27 is pivotally secured to the bearing plate 30. The bearing plate 30 is provided on the top surface with circular depressions 34 and 35 to receive the heads of screws 36 which extend through apertures provided in the bearing plate and registering apertures in the base plate.
- 70 The bearing plate 30 is provided with a bore 37 which opens into a counterbore 38 originating at the lower side of the bearing plate and houses the head of a screw 39 extending through an aperture in the base plate.
- 75 In order to adjust the angle member with reference to the base plate the angle member is swung about its pivot 31 to give access to the heads of the screws 36 which are then loosened or tightened as the case may be and subsequently the screw 39 is adjusted to engage the bottom of the counterbore 38. The vertical leg of the angle member is provided with a roller 40 which is secured in position by a bolt 41 having secured thereto a handle 42 so that the roller may be turned upon manipulation of the handle.
- 80
- 85
- 90
- 95
- 100

The roller 40 is formed as a grooved pulley and its inner circumference is knurled for a purpose hereafter explained. The horizontal leg 28 carries a plurality of washers 43 in superposed relation and provided with a central aperture for the passage of a bolt 44 which enters in threaded engagement in a screw threaded aperture 45 provided in the horizontal member 28. A roller 46 is arranged between the head of the bolt 44 and the topmost washer 43.

The vertical member 27 has pivotally secured thereto as at 47 a latch 48 which is adapted to engage with the lower side of the bearing plate 30 so as to lock the angle member to the bearing plate.

The device is primarily, although not exclusively, intended for the bending of corner beads so as to impart a curvature thereto. 20 The corner bead comprises the bead portion 49, the horizontal member 50 and the vertical member 51 which are, of course, integral. In operation the corner bead is introduced so that the horizontal member passes between 25 the rollers 19 and 20 of the U-members 12 and 26 and the vertical member 51 contacts with the guide roller 46. The roller 40 being slightly in a lower plane than the plane tangential to the lower roller 20 will 30 cause a bending of the bead 49 in the form of arc the radius of which is determined by the relative position of the rollers 40 and 20. If it is desired to impart a different curvature to the corner bead, then the latch 48 is released the angular member 27 is swung to the right as viewed in Fig. 4 and the screws 36 and 39 are adjusted to raise or lower the bearing plate 30 and therewith the roller 40 as requirements make it necessary, whereupon 35 the angular member is replaced in original 40 position and the latch 48 swung into engagement with the bearing plate. The roller 40 being provided with a knurled circumference will cause the corner bead to progress through 45 the device so that the same will become curved throughout its length. It is obvious that the curvature imparted to the corner bead may be accurately predetermined and that curvatures of various diameters may be imparted.

50 While the drawings show a preferred embodiment of the invention, various changes and alterations may be made without departing from the spirit of the invention.

I, therefore, do not limit my invention to 55 the details of constructions as shown, nor to the particular use described, but include all changes and alterations constituting departures within the scope of the invention as defined in the appended claims.

60 I claim:

1. A device of the character described, including a base, U-members secured thereto, pairs of rollers secured to the corresponding vertical legs of said U-members, a single roller secured to the other leg of said U-members,

and a knurled roller supported from said base between said U-members and having its lowermost peripheral point below the interspace of said pairs of rollers.

2. A device of the character described, including a base, spaced U-members, secured thereto, pairs of rollers secured to the corresponding vertical legs of said U-members, a single roller secured to the other leg of said U-members, a bracket adjustably secured to said base intermediate said U-members, and a knurled roller secured to said bracket with its nethermost peripheral point below the interspace of said pairs of rollers.

In witness whereof I affix my signature.

MONTE W. WALKUP.
